UNITED STATES PATENT OFFICE.

CHRISTINE SCHWARZ, OF CHICAGO, ILLINOIS.

GARMENT-RETAINER.

1,220,896.

Specification of Letters Patent. Patented Mar. 27, 1917.

Application filed November 9, 1914. Serial No. 871,063.

To all whom it may concern:

Be it known that I, CHRISTINE SCHWARZ, a citizen of the United States, and a resident of the city of Chicago, county of Cook, and 5 State of Illinois, have invented certain new and useful Improvements in Garment-Retainers, of which the following is a specification.

My invention relates to improvements in 10 garment retainers for women and more specifically to a device designed to adapt the same, when worn, to retain the waist band of the skirt and petticoat of the wearer in proper position.

15 A further object is the production of a device as mentioned, which will be of simple construction and efficient in use.

Other objects will appear hereinafter.

The invention consists in the combinations 20 and arrangements of parts hereinafter described and claimed.

The invention will be best understood by reference to the accompanying drawing forming a part of this specification, and in 25 which,

Figure 1 is a perspective view of a garment retainer embodying my invention,

Fig. 2 is a section taken on line $x-x$ of Fig. 1, and

30 Fig. 3 is a perspective view of the rear plate of the device detached.

The preferred form of construction as illustrated in the drawing comprises a belt 1 adapted, when the device is in use, to encircle 35 the waist of the wearer. Interposed in said belt is a suitable buckle 2 whereby the same may be adjusted to snugly embrace the waist of the wearer. Provided at the front side of belt 1 is a metallic plate 3 having slots 4 at its opposite edges for engagement 40 with the adjacent ends of said belt, as clearly shown in Fig. 1. Formed at the upper edge of the plate 2 is a hook 5 adapted, when the device is in use, to engage 45 over the waist band of the skirt of the wearer in order to hold the same against upward slipping. Also formed at the upper edge of plate 3 at either side of hook 5 are smaller hooks 6 positioned below said hook 5, the hooks 6 being adapted for engagement 50 with the waist band of the petticoat of the wearer also, in order to prevent the same slipping upwardly.

Depending from the plate 3 is a strap 55 7 provided at its lower end with a slotted

end piece or engaging plate 8 adapted for engagement with any one of the headed studs usually provided at the front side of a corset. The upper end of the strap 7 passes through spaced slots 9 and 10 which are 60 formed in the plate 3 adjacent the lower edge thereof, said end of said strap being releasably secured to said plate by means of pointed fingers 11 which are provided at the upper edge of the slot 10. Said fingers 65 are so arranged that downward pull upon the strap 7 will cause the upper end thereof to be drawn into engagement with the fingers 11 and thus be automatically locked in position. Also, with this arrangement it 70 will be seen that adjustment of the effective length of strap 7 may be secured by simply pulling downwardly upon the upper end thereof, it being clear that, when said end has been adjusted to the position desired, 75 and the lower end of strap 7 is pulled downwardly, the fingers 11 will automatically engage with said strap, to lock the same in adjusted position. With this arrangement, it will be seen, that two adjustments are 80 afforded for determining the vertical position of plate 3, namely, the adaptability of the end member 8 engaging with any one of the vertically spaced studs of the corset of the wearer, and the adjustment which is afforded 85 the strap 7 to regulate the effective length thereof. This being so, it will be seen, that when the device is in use, the same may be readily and easily adjusted to hold the skirt and petticoat waist bands at the 90 front down to any position desired.

Provided at the rear of the belt 1 is an elongated rectangular plate 1 having slots 13 at the ends thereof for the passage of said belt. The plate 12 affords means for engagement with hooks or other engaging devices which may be provided at the rear of the skirt or petticoat in order to support the latter and prevent sagging.

While I have illustrated and described the preferred form of construction for carrying my invention into effect, this is capable of variation and modification without departing from the spirit of the invention. I, therefore, do not wish to be limited to the 105 precise details of construction set forth, but desire to avail myself of such variations and modifications as come within the scope of the appended claim.

Having described my invention what I 110

claim as new and desire to secure by Letters Patent is:

In a device of the class described, a plate having vertical belt receiving slots in opposite sides thereof and a pair of central parallel horizontal slots, outwardly and downwardly inclined teeth formed on the upper edge of the lower horizontal slot, a central hook formed at the extreme upper central portion of said plate, and side hooks formed

at the upper side portions of said plate at a lower level than said central hook, substantially as described.

In testimony whereof I have signed my name to this specification in the presence of 15 two subscribing witnesses.

CHRISTINE SCHWARZ.
